US00D813213S

(12) **United States Design Patent** (10) **Patent No.:** **US D813,213 S**
(45) **Date of Patent:** **** Mar. 20, 2018**

(54) **HOME GATEWAY WITH A RADIO
FUNCTION**

(71) Applicant: **Toshiba Visual Solutions Corporation**,
Misawa, Aomori (JP)

(72) Inventor: **Tatsuya Honda**, Yokohama (JP)

(73) Assignee: **Toshiba Visual Solutions Corporation**,
Misawa, Aomori (JP)

(**) Term: **15 Years**

(21) Appl. No.: **29/589,268**

(22) Filed: **Dec. 29, 2016**

(30) **Foreign Application Priority Data**

Jul. 22, 2016 (JP) 2016-015662

(57) **CLAIM**

The ornamental design for a home gateway with a radio function, as shown and described.

DESCRIPTION

FIG. 1 is a front, top and right side perspective view of a home gateway with a radio function, showing my new design;

FIG. 2 is a front view thereof;

FIG. 3 is a right side view thereof;

FIG. 4 is a top view thereof;

FIG. 5 is a rear view thereof;

FIG. 6 is a bottom view thereof;

FIG. 7 is a perspective view showing a state in which the lens cover is rotated;

FIG. 8 is a sectional view, taken along line 8-8 in FIG. 2; and,

FIG. 9 is a sectional view, taken along line 9-9 in FIG. 4. The broken lines in FIG. 4 are included to indicate the cutting plane of FIG. 9. The broken lines shown in FIGS. 8 and 9 are for environmental purposes only and form no part of the claimed design.

1 Claim, 9 Drawing Sheets
